MACHINE FOR CORDING ORNAMENTATION

Sam Ross, Brooklyn, N. Y., assignor to Major Leather Supply Co., New York, N. Y.

Application November 11, 1935, Serial No. 49,143

3 Claims. (Cl. 41—1)

This invention relates to a machine for the production of ornamented leather and other materials.

An object of this invention is to provide a machine whereby a sheet of fabric or imitation leather having a cemented surface may be ornamented with raised lineal designs on its normally exposed surface and then cemented into unitary relation with a lower layer of fabric having a cemented surface.

Another object of this invention is to provide a machine whereby a plurality of cords may be secured between a two-ply fabric so as to ornament the upper layer with raised lineal designs known as cording.

Another object of this invention is to provide a machine having two co-acting rollers and means for bringing upper and lower layers of fabric and interposed cords between said rollers, and to rotate the rollers and cause the cords to be impressed into one of the layers of fabric in parallel relation and in predetermined parallel designs.

Another object of this invention is to provide a machine having two co-acting rollers, one of which has a plurality of wave-like parallel grooves and a wave-like cam at one end, and to provide control means whereby the wave-like cam causes corresponding wave-like motion of a plurality of cord holding members.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a cross-sectional view of the machine, the section being taken as on line 1—1 in Figure 3.

Figure 2 is a fragmentary sectional view, the section being taken as on line 2—2 in Figure 1.

Figure 3 is a plan view of the machine.

Figure 4 is an enlarged fragmentary portion of the cam end of the machine.

Figure 5 is fragmentary sectional view of the two rollers and showing a cord in the process of being impressed into a layer of fabric and uniting the two layers into unitary relation.

Figure 6 is an enlarged fragmentary longitudinal sectional view showing a plurality of cord holding members in operative position.

Figure 7 is a fragmentary sectional view of a

cord holding member, showing a cord tensioning arrangement.

Figure 8 is a plan view of a portion of fabric which has been ornamented with raised lineal designs visible on its normally exposed surface and known as cording.

Figure 9 is an enlarged cross-sectional view of the corded fabric, the section being taken as on line 9—9 in Figure 8.

In the illustrated embodiment of the invention the numeral 10 indicates a machine for ornamenting the leather and other materials and comprises an upper roller 11 having a plurality of grooves 12, 12, formed in parallel and wave-like relation in its outer surface. At one end of the roller 11 and coaxially therewith, there has been secured a cam 13 having a wave-like formation like the grooves 12 but facing in the opposite direction.

Mounted below the roller 11 and in parallel relation therewith is a roller 14 without any grooves in its outer surface. The rollers 11 and 14 have been rotatably mounted in bearings 15 and 16. A control arm 17 has been mounted on a pivot 18 secured in an arm 19. The arm 19 extends from the outer face of the bearing 16 and may be secured to said bearing by means of screws 20. At the free end of the arm 19 is a roller 21 mounted on a pin 22. The roller 21 fits in the wave-like groove 23 of the cam 13 and when the cam is rotated it causes the control arm 17 to vibrate.

Slidably mounted in apertures 24 and 25 in the bearings 15 and 16 is a bar 26 carrying a plurality of cord holding members 27, 27, arranged in parallel relation to each other and spaced apart so as to be adapted to align with the grooves 12, 12, in the roller 11.

At one end of the bar 26 is a pin 28 in engagement with an elongated aperture 29 at the lower end of the control arm 17. It will thus be seen that motion of the control arm at the cam end will cause motion in an opposite direction of the bar 26 and the cord holding members 27.

As shown in Figure 2, a gear 32 has been secured to the shaft 54 on which the roller 11 is mounted. A gear 30 has been secured to the shaft 31 on which the roller 14 is mounted. The gears 32 and 30 are in intermeshing relation and cause the rollers to rotate in opposite directions.

A drive gear 32 in intermeshing relation with the gear 30 has been mounted on a shaft 33 and a belt 34 on a pulley 35 may be employed to drive the gear 32 and impart motion to the rollers 11 and 14.

55

- Coil springs 36 have been mounted in the bearings 15 and 16 and bolts 37 serve for adjusting the tension of the springs and for bringing the rollers against each other by yielding pressure.
- 5 As shown in Figure 1, the cord holding members 27 are secured in the bar 26 by screws 38 and are preferably bent upwardly at one end. At the end adjacent the roller 11, the cord holding members 27 have upwardly pointing fingers 39 which 10 engage the respective grooves 12. The members 27 have springs 40, best shown in Figure 7. The springs are slightly spaced apart to receive the cords and serve to cause a tension on the cords 41 passing through apertures in the members 27.
- 15 As shown in Figures 1 and 5, an upper layer of fabric 43 and a lower layer of fabric 44 have been rolled between the rollers 11 and 14. The finger 39 seating in one of the grooves 12, has 20 pressed a lineal portion of the upper fabric into the groove 12 so as to provide room for a cord 41 to enter therein. It is to be noted that the lower surface 45 of the upper layer of fabric 43 and the upper surface 46 of the lower layer of fabric 44 have a layer of cement or other uniting composition applied thereto and when the machine 10 is in operation, the two layers of fabric are 25 pressed together and grip the cords 41 therebetween. The cemented layers are forced into engagement and are forcibly and adhesively 30 united by the pressing rollers and form a composite cemented fabric having raised lineal designs. The ornamented fabric may then be cut up into narrow widths for belt making or for ladies' hand bags or for other uses.
- 35 As shown in Figures 8 and 9, the composite fabric 47 made on the corded machine 10 shows raised lineal designs 48 visible on the normally exposed surface 49 of the said fabric.
- As shown in Figure 4, apertures 50 and 51 in 40 the bracket 19 and on opposite sides of the pivot 18 may be respectively used to receive the pivot 18 and reduce or increase the vibrations of the bar 26 and the cord holders 27 so as to permit the use of a roller 11 having different wave-like de-

signs of grooves than that shown in Figure 3 and to permit fabrication of differently ornamented composite fabrics than that shown in Figures 8 and 9.

I claim:

1. A machine for ornamenting a composite fabric with raised lineal cording designs, comprising an upper roller having a plurality of grooves arranged in parallel and wave-like relation in its outer surface and having a wave-like cam at one end, a lower roller mounted in adjacent parallel relation with the upper roller, means for bringing the two rollers against each other by yielding pressure, means for guiding a plurality of cords intermediate fabric layers and in 15 alinement with said wave-like grooves, and means for positively rotating said rollers in opposite directions.

2. A machine for ornamenting a composite fabric with raised lineal cording designs, comprising a roller having a plurality of grooves arranged in parallel and wave-like relation in its outer surface and having a wave-like cam at one end, a further roller mounted in adjacent parallel relation with said grooved roller, means for bringing the two rollers against each other by yielding pressure, means for guiding a plurality of cords intermediate fabric layers having cemented surfaces and in alinement with said wave-like grooves, and means for rotating said 30 rollers in opposite directions.

3. An apparatus for forming raised lineal parallel cording designs in a two-ply fabric, comprising a pair of spring pressed rollers, means for guiding a plurality of cords to said rollers, means to supply each cord under an individual tension, means to arrange the cords in parallel relation, one of said rollers having a plurality of design grooves formed in parallel relation in its outer surface, means for actuating said cords to cause 40 them to follow the path in said design grooves, and means for rotating said rollers in opposite directions.

SAM ROSS.
